BALL-UP DETECTOR

John E. McGowan, Forest Hills, Long Island,
N. Y., assignor to Miller Printing Machinery
Company, Pittsburgh, Pa.

Application June 10, 1937, Serial No. 147,414

8 Claims. (Cl. 192—126)

My invention pertains to devices for use in connection with machines, such as printing presses, to which sheets are fed one by one, for detecting the feeding of a sheet which is in a crumpled condition. Such devices are commonly known in the printing trade as "ball-up" detectors.

When a sheet is fed in a crumpled condition to a machine for operating thereon various harmful results are liable to follow. As one example of this in a cylinder printing press the crumpled sheet would present a greater than normal thickness of paper between the impression cylinder and the printing type or plates. Since a maximum pressure between the cylinder and the type, to give the required printing impression, may already obtain, the interposition of the extra thickness is likely to damage, or, "batter" the type or plates. Various automatic devices have heretofore been proposed for the purpose of avoiding such difficulties as this by throwing the impression cylinder out of printing position with respect to the type, or, more usually, stopping the press whenever a crumpled sheet is fed forward for being seized by the grippers of the printing cylinder.

It is the principal object of my invention to provide a detector device for this purpose which will be especially simple of construction and reliable in its operation.

Another object is to provide such a detector device which will work in conjunction with a device for detecting failures to feed a sheet, so that the instrumentalities for actually throwing out the impression of the press, or stopping the press, are available for both detector devices.

The detector device embodying my invention is shown, by way of example, in the accompanying drawings, and described in the following specification; but I wish it understood that the invention may be embodied in other forms and changes made in the particular form described and shown without exceeding the scope thereof as defined in the appended claims.

In the drawings:

Fig. 1 is a plan showing a portion of a frame, feed table, and one of the front drop-guides of a cylinder printing press, the drop-guide having associated therewith a detector device made in accordance with my invention;

Fig. 2 is a side elevation of the same, the press frame being omitted and the impression cylinder shown in section;

Fig. 3 is an enlarged plan of one of the drop-guides;

Fig. 4 is a side view of the same, partly in section; and

Figs. 5 and 6 are front views showing the gauge plate of one of the drop-guides, with the two detecting members carried thereby, Fig. 5 showing the detecting member for crumpled sheets in its inoperative position and Fig. 6 showing this detecting member in its operative position.

The press indicated in the drawings includes a frame 10 in which is rotatably supported, in 10 the usual manner, a cylinder 11, and with which is associated a feed table 12 upon which the blank sheets are fed, either by hand or automatically, into a position in which they are correctly placed for being drawn away by grippers 15 on the cylinder 11. At the front end of the feed table, is a lip plate 13, the leading edge of which comes close to the cylinder; and beneath the feed table is mounted a guide bar 14 upon which are supported a pair of tongues 15 of which only 20 one is shown, these tongues being adjustable laterally of the feed table. The front ends of the tongues 15 extend beyond the lip plate 13 and come into close proximity with the cylinder surface.

In suitable members such as that indicated at 16 is mounted a cross bar 17 upon which are secured a pair of front drop-guides 18, one only of which is shown. Each front guide consists of a casting 19 having a tubular portion 20 in 30 which is slidably mounted a stem 21, a spring 22 being interposed between the stem and the casting, and tending to press the stem 21 outwardly. Passing longitudinally through the casting 19 and threaded into the stem 21 is a 35 screw 23 having at its outer end a knurled head 24 with which engages a detent spring 25 mounted on top of the casting. To the front end of the stem 21 is secured a gauge plate 26 having ears 27 extending downwardly therefrom and spaced apart a distance something greater than the width of the associated tongue 15, so that when the gauge plate rests upon the tongue the ears will extend downwardly on each side of the latter, as shown in Figs. 5 and 6, thereby preventing the edge of the sheet from entering beneath the gauge plate. A fine adjustment of the gauge plate towards and from the feed table can be effected by rotating the knurled head 24 manually, such head being retained in its ad- 45 justed position by means of the detent spring 25.

By manipulating the knurled heads 24 of the two front guides, and by adjusting a side register device on the feed table (of which many kinds are well known in the art), the position of the 50 55

sheet on the cylinder can be determined with great accuracy. The sheet is, of course, fed against the gauge plates 26 of the front guides, so that its front edge is exposed, except for those portions which lie on the tongues 15. From this position it is withdrawn by the grippers on the cylinder 11, the front guides being made to rise, in a well known manner, to permit this.

For detecting the presence or absence of a sheet at the gauge plates 26 of the front guides, each gauge plate has pivoted thereto a detecting member 28, which includes a pair of arms 29 connected by a pin 30 which is pivotally mounted in ears 31 extending rearwardly from the gauge plate. The arms 29 are connected by a front portion 32 having a downwardly extending leaf 33 and an upwardly extending leaf 34. The downwardly extending leaf 33 is adapted to enter a slot 35 formed in the associated tongue 15, and the arms 29 are provided with a counterweight 36 which tends to swing the whole detecting member 28 into a position in which the leaf 33 stands in the slot 35 in a position in advance of the gauge plate 26, as indicated in Fig. 4.

The stem 21 is made hollow and contains a plunger 37 which is normally pressed outwardly by means of a spring 38 disposed between said plunger and the end of the screw 23, the possible outward movement of the plunger being limited by a screw 39. The plunger protrudes from the front end of the stem 21 and is formed at that point with a head 40 having an annular groove 41 formed therein. The position and dimensions of the parts are such that when the detector member is in its normal position, shown in Fig. 4, its upper leaf 34 will be disposed in the groove 41, and will prevent movement of the plunger inwardly with respect to the stem 21. When, however, a sheet is fed correctly, so that its edge comes into registering engagement with the gauge plate 26, such edge will push the lower leaf 33 forward, rocking the detector member about its pivot, and cause such lower leaf to enter a slot 42 formed for the purpose in the gauge plate 26. Such rocking movement of the detector member will cause its upper leaf 34 to swing forward into a position in which it no longer enters the groove 41 of the plunger 37. In these circumstances, the plunger 37 is free to move inwardly with respect to the sleeve 21. It is the fact of whether or not the plunger 37 is free for inward movement that controls whether the press shall continue to print, or whether it shall be stopped, or its impression shall be thrown off.

Extending across the feed table 12 is a rock shaft 43 operated upon by a torsion spring 44, or some other means tending to rock the same in a clockwise direction, when viewed as in Fig. 6. Such rock shaft has mounted for lateral adjustment thereon a pair of tappet levers 45, one for each of the front drop guides. These tappet levers have engaging portions 46 which, when the parts are adjusted, stand opposite the heads 40 of the plungers 37. At its outer end, the shaft 43 is provided with a lever 47 having an abutment portion 48 which lies above a vertically reciprocable rod 49. The details of the mechanism actuating, and actuated by, the rod 49 are not of interest here. The rod is reciprocated once for each cycle of the press, thereby, by its engagement with the abutment portion 48, causing the shaft 43 to rock against the action of its spring 44, and then return. The mechanism, further, is such that when, at a time when a

sheet should be presented to the front guides, the spring 44 does not, through the lever 47, exert its pressure downwardly upon the rod 49, the press will either be stopped, or the impression of the press will be thrown off, or both, according to how it is desired to constitute the mechanism. Usually the press will be stopped. When, however, at that period, pressure of the spring 44 is exerted downwardly on the rod 49, the press will continue to print.

When the sheets are fed correctly, so as to make registering engagement with the gauge plates 26 of the front guides, the detecting members 28 will be pushed forward so that their upper leaves 34 pass out of the slots 41 of the plungers 37. Under these conditions, when the rod 49 descends, the engaging portions 46 of the tappet levers 45 can push the plungers inwardly with respect to the stems 21, and accordingly the shaft 43 can rock clockwise under the action of its spring 44, the latter exerting a downward thrust upon the rod 49. Under these conditions, the press will continue to print. When, however, a sheet does not reach the gauge plates 26 of the front guides, the detector members 28 will remain in the position shown in Fig. 4, in which the upper leaves 34 lie in the grooves 41 of the plungers 37. In these circumstances, when the rod 49 descends and the spring 44 causes the engaging portions 46 of the tappet levers 45 to push against the heads 40 of the plungers 37, the latter are prevented, by the upper leaves 34, from moving inwardly, and the shaft 43 is thereby held against further rocking movement. Thus the spring 44 cannot exert any downward pressure upon the rod 49. Under these conditions, the press will either be stopped, or its impression will be thrown off, or both, according to how the mechanism is constituted. There are two of the front guides and associated detecting members, either of which functions separately. Therefore if a sheet should be fed properly against the gauge plate 26 of one front guide, but not against the other, the press stoppage, or impression throw off, or both, will occur, as will also take place if a sheet having a portion of its front edge torn away should present itself.

The detecting member 28, the operation of which has just been described, functions whenever a sheet is not fed to the drop-guides or when a sheet having a torn front edge is fed. A crumpled sheet would be fed into the press, which would continue running in the ordinary manner, providing that portions of such crumpled sheet reached and moved both of the detecting members 28. To prevent this I provide, upon the gauge plate 26 of each drop-guide, a second detecting member, 50, such member being pivoted, at 51 (Figs. 5 and 6) to the gauge plate to one side of the vertical center thereof. At the other side of the center of the gauge plate the detecting member is provided with a downwardly extending leg 52 formed with a forwardly extending foot 53 which is disposed parallel with the adjacent tongue 15 and terminates in an upwardly inclined portion 54. Extending upwardly from the detecting member is an arm 55 having a lateral lug 56 disposed opposite the annular recess 41 of the plunger-head 40. As will be seen, the foot 53 of the detecting member normally rests upon the tongue 15, and the parts are so constructed and positioned that, in these circumstances, the lug 56 is out of the recess 41 of the plunger-head 40. However, if a sheet crumpled at or near its front edge (the most usual place

where crumpling is encountered) should be fed so as to reach the gauge plates of the drop-guides the crumpled portion of such sheet, in entering beneath the foot 53 of the detecting member 50, will cause such member to tilt upwardly about its pivot 51 into the position shown in Fig. 6, in which the lug 56 would enter the recess 41 of the plunger-head, preventing inward movement of the plunger, in the manner that has been described above, with respect to the leaf 34 of the detecting member 28 and causing either the impression of the press to be thrown off or the press to be stopped, or both.

It will immediately be appreciated that the invention is characterized by an important advantage over prior devices which are effective to stop the press only in case of failure to feed a sheet or in case of the feeding of a sheet with a torn edge. The invention provides the additional safeguard against the feeding of crumpled sheets which is just as undesirable as the operation of the press in the absence of a sheet or with a torn sheet.

Although I have illustrated and described herein but a preferred embodiment of the invention, changes in the construction and operation disclosed may be made without departing from the spirit of the invention or the scope of the appended claims.

30 I claim:

1. The combination with a printing-press sheet feed including periodically operating means preventing a stoppage of the press, a retractile plunger, means operating with said first mentioned means for retracting said plunger, and means actuated to inoperative position by the feeding of a sheet, normally preventing retraction of said plunger, of means normally ineffective but operable by the feeding of a balled-up sheet into position to prevent retraction of said plunger.

40 2. The combination with a printing-press sheet feed, of means effective, unless operated on each cycle of the press, to suspend operation of the press, a retractile plunger, means actuated on operation of said first mentioned means to retract the plunger, and a detector movably mounted adjacent said plunger and operable into a position preventing retraction of the plunger, on feeding of a balled-up sheet.

45 3. The combination with a printing-press sheet feed, of means effective, unless operated on each cycle of the press, to suspend operation of the press, a retractile plunger, means actuated on operation of said first mentioned means to retract the plunger, and a detector pivoted adjacent said plunger and movable into a position preventing retraction of the plunger, by the feeding of a balled-up sheet.

4. The combination with a printing-press sheet feed, of means effective, unless operated on each cycle of the press, to suspend operation of the press, a retractile plunger, means actuated on operation of said first mentioned means to retract the plunger, and a detector movably mounted adjacent said plunger and operable into a position preventing retraction of the plunger, said detector having a foot adapted to be engaged by a crumpled sheet.

5 5. The combination with a printing-press sheet feed, of means effective, unless operated on each cycle of the press, to suspend operation of the press, a retractile plunger, means actuated on operation of said first mentioned means to retract the plunger, and a detector movably mounted adjacent said plunger, said detector comprising a lever pivoted above the path of travel of the sheet on an axis substantially parallel thereto, and having an upturned foot whereby it is operated into a position preventing retraction of said plunger, by the feeding of a crumpled sheet.

10 6. In a printing press, the combination with means normally operated periodically to prevent suspension of operation of the press, and means operated therewith for retracting a yieldable plunger, of a lever pivoted adjacent said plunger, normally preventing retraction thereof, but tilted to an ineffective position by arrival of a sheet, and a second lever adjacent said plunger and normally ineffective but tilted to a position in which it locks said plunger against retraction, by the arrival of a crumpled sheet.

15 7. A ball-up detector for the sheet-feed of a printing press, having means normally operated periodically to prevent suspension of operation of the press including a yieldable plunger and means for retracting it, said detector comprising a lever pivoted below said plunger, said lever having a portion adapted to be engaged and displaced by a crumpled sheet and a portion adapted to be moved thereby into position to lock said plunger against retraction.

20 8. In a sheet feed, for a printing press, a gauge for arresting a sheet, a lever pivoted thereadjacent so as to be actuated by a sheet advanced to said gauge, a plunger reciprocably mounted adjacent said lever, said lever having a portion normally preventing retraction of said plunger, a second lever pivoted adjacent said gauge and having a portion effective on tilting of the lever to prevent retraction of said plunger, and means on said second lever adapted to be engaged by a crumpled sheet approaching said gauge whereby to tilt the second lever.

25 30 35 40 45 50 55 JOHN E. McGOWAN.
